Fig. 3

FIG. 1 is a front elevational view of a toy puppet embodying my new design;

FIG. 2 is a side elevational view of the toy puppet, the opposite side being identical thereto; and

FIG. 3 is a rear elevational view of the toy puppet.

The toy puppet is completely covered with a fur-like material but has been omitted from the body in the views for convenience of illustration.

I claim:

The ornamental design for a toy puppet, as shown and described.
